[57] CLAIM

The ornamental design for a periapical exposure dental x-ray film holder, as shown and described.

DESCRIPTION

FIG. 1 is a front elevational view of a periapical exposure dental x-ray film holder, showing my design;

FIG. 2 is a rear elevational view thereof;

FIG. 3 is a top view of FIG. 1 with portions broken away for clarity of illustration;

FIG. 4 is a bottom view of FIG. 2;

FIG. 5 is left end elevation; and

FIG. 6 is a right end elevation.

The film, which is represented by broken lines, is shown for illustrative purposes only.
